UNITED STATES PATENT OFFICE

2,610,641

LIPSTICK APPLICATOR

Mildred H. Ivey, Atlanta, Ga.

Application October 22, 1951, Serial No. 252,534

2 Claims. (Cl. 132—88.7)

1

This invention relates to a lipstick applying means.

An object of this invention is to provide an applicator for smoothing lipstick so that the lipstick will be evenly applied and the outlines thereof will be relatively sharp.

Another object of this invention is to provide a lipstick applicator which can be adapted for various types of lips and can be easily maintained in a clean and sanitary condition.

A further object of this invention is to provide a lipstick applicator which can be made out of metal, plastic or the like, and can be readily carried in a purse.

With the above and other objects in view, my invention consists in the arrangement, combination and details of construction disclosed in the drawings and specification, and then more particularly pointed out in the appended claims.

In the drawing:

Figure 1 is a detailed side elevation partly broken away and in section of a lipstick applicator constructed according to an embodiment of this invention.

Figure 2 is a plan view of the device.

Figure 3 is a front elevation of the device showing diagrammatically the way in which the device is used.

Figure 4 is a transverse sectional view taken on the line 4—4 of Figure 2.

Referring to the drawing, the numeral 10 designates generally a longitudinally-split tubular member which may be formed out of a flat sheet of metal which is stamped or otherwise formed into a tube. The tubular member 10 is formed with oppositely disposed cut-outs 11 which form finger notches and provide a substantially semi-cylindrical extension projecting from each end of the member or body 10. The opposite ends of the extensions 11 are formed on an oblique angle as indicated at 12, and the upper edges of each extension are formed with an upwardly and inwardly inclined edge 13. The outer end of each extension, which is generally designated as 14, is formed with a beveled or rounded edge 15 so that when the device is inverted with the open side of an extension positioned in confronting relation to a lip, the outer end 15 will not present a sharp corner to the lip. The curved end 15 is pressed firmly against the lip upon which the lipstick has been applied, and the device is then moved, as an example, from the center of the lip outwardly with one oblique edge 12 moving along the upper outline of the lip so that this end 12 will not only smooth out the lipstick, but

2

will also prevent any lipstick from being smeared beyond the marginal edge of the lip. As shown in Figure 2, one end 16 of the device is substantially wider than the opposite end so that this device may be used for lips of different sizes.

The device may be formed out of metal which may be stamped from the flat sheet, or, if desired, may be formed out of plastic which is molded to the configuration shown.

- 10 Any excess lipstick which may be removed from the lips by movement of the device thereof may be cleaned from the inside or the concave side of the device very easily so that the device may be kept in a clean and sanitary condition at all times. In the use of this device, the lipstick is applied to the lips in the normal manner, and then the device is rubbed over the lips after the manner shown in Figure 3 with one end pressed firmly against the lip and the device moved across the lipstick and the lip.

This device may also be used in a vertical movement by disposing the end 15 at the upper edge of the lip line and drawing the end 15 downwardly. The operation is started at the center of the lip working outward with a succeeding stroke slightly overlapping a preceding stroke.

What is claimed is:

1. A device for smoothing lipstick comprising a tubular body, and transversely arcuate members projecting from the opposite ends of said body, the opposite lengthwise edges of each member adjacent said body being formed with finger engaging cutouts, and the outer end of each member being formed with a rounded edge on the inner concave side thereof.

2. A device for smoothing lipstick comprising a tubular body, and transversely arcuate members projecting from the opposite ends of said body, the outer end of each member being angularly formed relative to the length thereof, said angularly formed ends converging in the direction of the concave sides of said members and each member having a rounded edge on the inner concave side thereof at the outer end of said member.

MILDRED H. IVEY.
